SCREENING APPARATUS

Wilbur E. Koonce and Charles F. Story, Laurel,
Miss., assignors to Masonite Corporation,
Laurel, Miss., a corporation of Delaware

Application October 11, 1948, Serial No. 53,966

4 Claims. (Cl. 210—150.8)

1

This invention relates to an apparatus for reclaiming fiber and more particularly to a screening apparatus for reclaiming usable fiber from the effluent resulting from reducing the water content of fibrous stock for making fiber board and paper.

In the manufacture of fiber boards, e. g., wood chips are fiberized, the fiber is refined, washed, screened on about a 65 mesh screen and then formed into a wet lap from which the board product is made. The effluent (material passing through this screen) contains suspended solids in about 99% water. The amount of such solids on a dry weight basis is approximately 16% of the fiber retained on this screen. These solids may be divided into essentially two fractions of about the same magnitude. One fraction is substantially fibrous and the other fraction is substantially non-fibrous and of a gelatinous-like nature.

Although the fibrous fraction may contain some non-fibrous material and the non-fibrous fraction may contain some fiber, the two fractions are substantially of the fibrous and non-fibrous type materials.

If properly reclaimed the fibrous fraction may be used to advantage in making boards or paper by adding back to the wet lap fiber, the reclaimed fraction being about 5% dry weight basis of the wet lap fiber retained on the 65 mesh screen. Reclaiming the fibrous fraction of this effluent in a suitable state for adding back to the system to make boards and paper is the primary aim of this invention.

Although the need of reclaiming this fiber from the effluent has been recognized for some time, it has remained an unsolved problem of considerable difficulty until the present invention was made. Prior art apparatuses are unsuitable for this purpose because they are not adapted to recover fiber from effluent of this nature so as to obtain the fiber in a condition suitable for use. The complexity of the problem is due in part to the characteristics of the fibrous and non-fibrous fractions of the effluent. A major difficulty is due to the fact that the fibrous fraction has a high affinity for the non-fibrous fraction, and hence separating the two presents a difficult problem. Unless substantially all the non-fibrous material is removed it produces an inferior board or paper product.

It has been found according to this invention broadly that the deficiencies of prior art apparatus are overcome by providing and employing an apparatus comprising a feed supply means for the fibrous material; fiber removal means; a screen; a feed diffuser means; and sprays.

A preferred embodiment of this invention will be more fully illustrated by referring to the draw-

ings wherein identical reference numerals are used to indicate similar parts in the figures.

Referring to the drawings generally:

Figure 1 is a side elevation in partial section showing the relative combination of component parts of the invention.

Figure 2 is a plan view of Figure 1 showing further details of the apparatus.

Referring now to the drawings in greater detail, the apparatus according to a preferred embodiment of this invention comprises a feed supply trough 1 for the fibrous material being processed; a conduit 2 for introducing the fibrous feed; a baffle 3 for maintaining an even flow of the feed; a fiber removal trough 4 positioned forward and below the feed supply trough; a fixed screen 5 extending from the supply trough to the fiber removal trough, the screen presenting an inclined surface portion 5-A adjacent to the feed supply trough and substantially a horizontal surface portion 5-B adjacent to the fiber removal trough; a feed diffuser 6 above a part of the inclined portion 5-A of the screen in spaced-apart and substantially parallel relationship therewith and extending from the feed supply trough; and sprays 7 positioned above the substantially horizontal portion 5-B of the screen. Preferably the portion 5-B of the screen has a slight declination, as for example roughly two degrees.

The feed diffuser 6 is a composite unit made of a series of trough-like compartments 8 having greater depth than width and having small openings or perforations 9 in the bottom thereof. The compartments are so arranged with respect to each other and the feed supply trough as to allow the feed to overflow from the feed supply trough and fill the feed diffuser by overflowing from one compartment to the succeeding compartment. The side walls of the compartments are imperforate or solid. Since the several compartments of the diffuser are filled with feed supply, substantially equal head pressure is obtained in the compartments and the feed supply is thus fed to the screen over a large area under substantially equal head pressure.

The screen 5 is supported on trusses 10 and 11 which in turn are supported by posts 12. The aprons 13 and 14 direct the watery screenings into the conduit 15 through which they flow from the apparatus.

In practicing this invention according to a preferred embodiment thereof, effluent, which has passed a screen of about 65 mesh in reducing the water content of watery fibrous stock for fiber board manufacture, is passed into the feed supply trough 1 through conduit 2. When this trough fills, the feed flows over the entire front wall 16 of the feed supply trough and quickly fills the first compartment 17 of the feed diffuser

6. Feed from the first compartment 17 flows over the entire back wall 18 of the next compartment 19 and fills it. In like manner all the feed diffuser compartments are filled. The rate of feed then is adjusted so that the overflow continues throughout the operation. The baffle 3 serves to equalize the flow of feed to the diffuser. The feed flows through openings 9 in the bottom of the compartments and strikes the inclined portion 5-A of the screen. Directional arrows A indicate the feed flow.

The feed diffuser plays an important part in this invention. It supplies a very even and smooth flow of feed to the screen. It aids in breaking up foaming of the feed, foaming being an inherent characteristic of the effluent which makes screening difficult. The feed diffuser also helps to wash the non-fibrous solids from the fiber, for which, as pointed out hereinbefore, the fiber has a strong affinity. Further, the diffuser aids in screening by increasing the feed-screen contact time in that the flow of feed from each compartment impedes the flow of feed over the screen which has come from the preceding compartment. An additional advantage of the diffuser is that it increases the life of the screen by a large factor. Without the diffuser all the feed would impinge on the screen and rapidly wear it out along a line just below the feed supply trough.

The partially screened feed then passes to the substantially horizontal portion 5-B of the screen where it is treated further. This portion of the screen checks the forward velocity of the feed and permits more time to further treat the feed on a smaller surface of screen than otherwise would be possible. Best results are obtained if this portion 5-B of the screen is sloped slightly downward from the horizontal from the inclined portion 5-A of the screen to the fiber removal trough 4. As the feed passes over this portion 5-B of the screen, the remaining non-fibrous solids are washed from the fiber with water from the sprays 12. The sprays also aid in breaking up foam remaining or formed after passage from the portion of the screen beyond the feed diffuser. However, the tendency of the feed to foam lessens as it approaches the exit end of the screen. The refined fiber passes from this substantially horizontal portion 5-B of the screen into the trough 4. The fiber flows from trough 4, as indicated by the arrows B, and is passed into a storage tank back into the system where it is used along with the usual fiber in making fiber boards.

Along the entire screen undesirable materials are being removed from the feed as indicated by the arrows C.

As many apparently widely different embodiments of this invention may be made without departing from the spirit and scope thereof, it is to be understood that the invention is not limited to the specific embodiments thereof except as defined in the appended claims.

We claim:

1. Apparatus for reclaiming usable fiber from the effluent resulting from reducing the water content of fibrous stock for making fiber board and paper, which comprises a feed supply means; fiber removal means positioned forward and below the supply means; a fixed screen extending from the supply means to the removal means, said screen presenting an inclined surface portion adjacent to the supply means and a substantially horizontal surface portion adjacent to the

removal means; a feed diffuser means above said inclined portion of the screen in spaced-apart and substantially parallel relationship therewith and extending from the supply means, said diffuser means including a composite unit of a series of interconnected troughlike compartments having imperforate side walls and having perforations in the bottom thereof and extending across the upper part of said inclined portion of the screen, said compartments having a greater depth than width and being so arranged as to allow the feed to overflow from one compartment to the succeeding compartment and flow through the bottom perforations of each compartment to diffuse the feed over a substantial area of the inclined portion of the screen under substantially equal head pressure; and sprays positioned above said substantially horizontal portion of the screen.

2. Apparatus as defined in claim 1, and in which said substantially horizontal portion of the screen slopes slightly downward from the horizontal from said inclined portion of the screen to said fiber removal means.

3. Apparatus for reclaiming usable fiber from the effluent resulting from reducing the water content of fibrous stock for making fiber board and paper, which comprises a feed supply means; fiber removal means positioned forward and below the supply means; a fixed screen mounted on stationary supports and extending from the supply means to the removal means, said screen presenting an inclined surface portion adjacent to the supply means and a substantially horizontal surface portion adjacent to the removal means; a feed diffuser means above a part of said inclined portion of the screen in spaced-apart and substantially parallel relationship therewith and extending from the supply means, said diffuser means including a composite unit of a series of interconnected troughlike compartments having imperforate side walls and having perforations in the bottom thereof and extending across the upper part of said inclined portion of the screen, said compartments having a greater depth than width and being so arranged as to allow the feed to overflow from one compartment to the succeeding compartment and flow through the bottom perforations of each compartment to diffuse the feed over a substantial area of the inclined portion of the screen under substantially equal head pressure; and sprays positioned above said substantially horizontal portion of the screen.

4. Apparatus as defined in claim 3, and in which said substantially horizontal portion of the screen slopes slightly downward from the horizontal from said inclined portion of the screen to said fiber removal means.
